UNITED STATES PATENT OFFICE.

WILLIAM W. JONES, OF ALBANY, NEW YORK.

FUSE-RETAINER.

1,097,442.

Specification of Letters Patent.

Patented May 19, 1914.

Application filed September 16, 1913. Serial No. 790,116.

To all whom it may concern:

Be it known that I, WILLIAM W. JONES, a citizen of the United States, residing at Albany, in the county of Albany and State of New York, have invented new and useful Improvements in Fuse-Retainers, of which the following is a specification.

The general object of the invention is to keep the strain off the point of connection between a blasting cartridge and a fuse while such cartridge is held suspended by the fuse, as in the act of lowering the cartridge into a hole, or when the charge is arranged in such other position as might result in the accidental disengagement of the fuse from the cartridge. And to this end the invention resides in embodying an anchor in the explosive material located within the cartridge, extending one end portion of this anchor beyond one end of the cartridge and adapting this said end portion of the anchor to be adjusted onto a portion of the fuse farther from the end of the cartridge than the said end portion of the anchor, whereby to have that portion of the fuse between the anchor and the end of the cartridge slack, and the weight of the cartridge thrown onto the anchor when the cartridge is suspended by the portion of the fuse located beyond the anchor.

Other objects will appear and be better understood from that embodiment of my invention of which the following is a specification, reference being had to the accompanying drawings forming part hereof, in which:

Figure 1 is a perspective showing my invention in use in connection with a blasting cartridge and powder fuse. Fig. 2 is a view similar to Fig. 1 but showing the invention in use in connection with an electric ignition device. Fig. 3 is a detail perspective of the invention.

The fuse holder herein indicated generally by *a* comprises an engaging end 5, an attaching end 6 and a body portion connecting the ends 5 and 6 and indicated by 7.

The length of the body portion 7 will be so proportioned with respect to the length of the cartridge with which it is to be connected, as to admit of having a considerable portion of the said body 7 located within the cartridge and yet have the attaching end spaced for a considerable distance from one end of the cartridge when the device is in

use. Therefore, the length of the holder *a* may be greater if so desired, than the length of the cartridge herein indicated by 8. By having the lengths of the cartridge and holder proportioned as just stated or as shown in the drawings, the engaging end 5 may be arranged at the bottom of the cartridge 8 and a more effective anchoring of the holder had than there would be if the attaching end were arranged nearer the top of the cartridge. It will, of course, be understood, however, that for purposes of my invention it is immaterial as to the distance which the engaging end may be spaced from the lower end of the cartridge when the device is in use.

In assembling my device with a cartridge such as indicated at 8 and to have the various parts in the relative positions shown in the drawings, the engaging end 5 is introduced into the shell while the same is empty and brought to a point adjacent to the lower end of the said shell when the same is positioned as viewed in the drawings. When the holder is so positioned the upper or attaching end portion 6 thereof will be beyond the upper end of the shell. The explosive material is then introduced into the shell in the ordinary manner and packed around the portion of the body 7 located within the shell after which the upper end of the shell is sealed, thus the cartridge is completed. The engaging end 5 may be of any construction that will prove effective in preventing the easy withdrawal of the body 7 from the material in which it is embedded, preferably the said engaging end 5 will be greater in diameter than the diameter of the body 7. Now the said body 7 and engaging end 5 may be formed of any material found suitable for the purpose and may be either rigid, semi-rigid, or flexible. A cheap and effective material for forming the body 7 and engaging end 5 is found to be stout twine. With this substance the engaging end may be conveniently formed by tying several knots in one end of the twine after the same has been doubled.

The attaching end 6 may be formed of any material found suitable for the purpose, as fiber. In the present instance, this attaching end 6 is shown in the form of an oblong plate with an opening 9 at one end thereof to facilitate its attachment to the body 7 which attachment may be readily effected.

by passing one end of the body through the opening 9 and then passing the engaging end 5 between the doubled twine.

10 and 11 indicate openings in the plate forming the attaching end, which openings are of a size to effect a slight contraction of a piece of ordinary powder fuse, such as is shown at 12 in Fig. 1 of the drawings, when the said fuse is laced through these openings, as shown. By having the said openings 10 and 11 so proportioned to the cross sectional area of the fuse as to slightly contract that portion of the fuse disposed in the openings, the said attaching end will frictionally bind on the fuse, and further by disposing the openings and lacing the fuse therethrough as shown, slipping of the said fuse will be prevented when the cartridge is held suspended thereby or when the fuse is given an ordinary pull.

Now when the fuse is laced through the attaching plate and one end of the fuse inserted into the upper end of the cartridge 8 and the attaching plate adjusted to a point 25 on the fuse which is farther from the top of the cartridge than is the lower opening 11 when the parts are positioned as shown in Fig. 1, then the weight of the cartridge will be on the attaching plate and a portion of the fuse beyond the said plate when the cartridge is suspended, as before stated.

With the form shown in Fig. 2 the conducting wires 13 and 14 extending from the detonator 15 embedded in the cartridge, are wrapped around the attaching plate 6 after having been passed through the lower opening 11 thereof, and thence directed through the upper opening 10 and to a source of electric energy and a suitable controlling device (not shown).

What is claimed as new is:

1. In combination, a cartridge, a fuse and a fuse holding device, the said fuse having one end directed into one end of the cartridge and the said holding device having one end directed into the same end of the car-

tridge as the fuse and its opposite end adjustably connected to the fuse.

2. In combination, a cartridge, and a fuse holding device, the said holding device having one end directed into one end of the cartridge and its opposite end portion provided with openings, and a fuse laced through the openings of the holding device and directed into the same end of the cartridge as the holding device.

3. In combination, a cartridge, and a holding device, the said holding device having one end directed into the cartridge shell and surrounded by the explosive material within the shell and its opposite end provided with a plate adapted for attachment to a fuse.

4. In combination, a cartridge, and a fuse holding device, the said fuse holding device comprising a body having one end directed into one end of the cartridge shell and into the explosive material within the shell, means associated with this last-named end of the body and coacting with the explosive material within the shell to prevent the withdrawal of the body, and an attaching plate at the opposite end of the body and adapted to be adjustably connected to a fuse.

5. A fuse holder for cartridges, comprising a body portion having an engaging end and an attaching end, the former being adapted to be connected to a cartridge and the latter to be adjustably connected to a fuse.

6. A fuse holder for cartridges, comprising a flexible body portion having an engaging end and an attaching end, the former being adapted to be connected to a cartridge and the latter to be adjustably connected to a fuse.

In testimony whereof I affix my signature in presence of two witnesses.

WILLIAM W. JONES.
